UNITED STATES PATENT OFFICE

CHARLES N. MONTEITH, ROBERT J. MINSHALL, AND JOHN C. SANDERS, OF SEATTLE, WASHINGTON, ASSIGNEES TO BOEING AIRPLANE COMPANY, OF SEATTLE, WASHINGTON, A CORPORATION OF WASHINGTON

DESIGN FOR AN AIRPLANE

Application filed April 18, 1932. Serial No. 43,535. Term of patent 7 years.

To all whom it may concern:

Be it known that we, CHARLES N. MONTEITH, ROBERT J. MINSHALL, and JOHN C. SANDERS, citizens of the United States, residing at Seattle, in the county of King and State of Washington, have invented a new, original, and ornamental Design for Airplanes, of which the following is a specification, reference being had to the accompanying drawings, forming part thereof.

Figure 1 is a plan view of the airplane, showing our new design.

Figure 2 is a front elevation of the same in flight.

Figure 3 is a side elevation of the airplane in flight.

We claim:

The ornamental design for an airplane, as shown.

Signed at Seattle, King County, Washington, this 28th day of March, 1932.

CHARLES N. MONTEITH.
ROBERT J. MINSHALL.
JOHN C. SANDERS.
